UNITED STATES PATENT OFFICE.

EMILE PIQUEREZ, OF PARIS, FRANCE, ASSIGNOR TO ALEMITE MANUFACTURING CORPORATION, OF CHICAGO, ILLINOIS, A CORPORATION OF DELAWARE.

LUBRICANT COMPRESSOR.

Application filed April 15, 1925, Serial No. 23,283, and in France October 14, 1924.

This invention relates to lubricant compressors, and more specifically to a large, semi-portable type for use in service stations and under similar conditions of service.

5 Among the objects of the invention may be mentioned a detachable connection between the piston of the reservoir cylinder and its guide rod. This connection may be obtained by the operator at will for carrying 10 out certain manipulations such as the elimination of air mixed with the lubricant in the reservoir, or the lifting out of the piston itself for filling purposes.

15 The guiding tube for the reservoir piston may also be clamped to the cover of the reservoir when the rod is to be used for moving the device itself.

20 The invention also relates to a novel means for actuating the piston rod of the lubricant compressor itself by means of a pivoted foot pedal.

25 The single figure of the accompanying drawing illustrates, in longitudinal section, a double action compressor embodying these improvements.

In the embodiment of the invention selected for illustration, the movable piston of the reservoir 1 comprises a central sleeve 2 having an enlarged head 2' and threaded 30 to receive a lock unit nut 3 for the elastic clamping against the head 2' of the clamping plates constituting the piston itself. In the wall of sleeve 2, which is bored to receive the guide rod 4, there are formed bayonet 35 slots 5, and guide rod 4 carries a transverse pin 6 to enter the slots when the rod is drawn up through the sleeve 2. This engagement may be obtained by a vertical entering movement followed by a movement of rotation in a horizontal plane, and will be employed when it is desired to get rid of air mixed in the lubricant. For this purpose, the device is provided with a plug 7 having a knurled head and threaded into 40 the bottom of the reservoir, being provided with a flat spot 7'. Liberation of air may be effected by unscrewing the plug slightly and operating the piston by means of rod 4 connected thereto by the bayonet slots above 45 described.

50 Rod 4 terminates in a handle 9 and passes through the cover 8. It may be clamped

to the cover by means of a set screw 10 having a knurled head.

The operating rod for the compressor piston 11 ends in a clevis 12 pivoted to a bent lever 13. This lever is also connected to a supporting link 14 pivoted on ears 15 carried by the bottom of the reservoir, and its long arm 13' is drawn toward the reservoir 60 by coil spring 16 which normally holds the lever in the dotted line position.

To operate the compressor, lever 13 is pushed down with one foot, which moves piston 11 down and compresses the lubricant below it in the annular space between its piston rod and the compression cylinder 17. The compressed lubricant may be delivered by the lateral opening 18 (provided with a connector and flexible tube, not shown) when the pressure has risen sufficiently to push down valve 19. The compression stroke ends when the piston itself makes contact with the valve, and the spring 20 yields. Upon relief of foot pressure, 75 spring 16 draws lever 13' to its initial position while valve 19 again closes the compression cylinder and the piston, developing suction below itself, uncovers, at the upper end of its stroke, the admission ports 21.

The device shown rests on three feet 22, 22 and 23, and it is provided with wheels 24 on axles journaled in feet 22 so that when the device is in its vertical position of use, the wheels are off the ground. To move 85 the device, rod 4 is clamped in cover 8 by means of set screw 10, and handle 9 may be used to tip the device onto wheels 24 and move it around.

Without further elaboration, the foregoing will so fully explain the gist of the invention, that others may, by applying current knowledge, readily adapt the same for use under various conditions of service without eliminating certain features which may 90 properly be said to constitute the essential items of novelty involved, which items are intended to be defined and secured by the following claims.

I claim:

1. A lubricant compressor comprising a reservoir, an axially slid able rod extending out through the top of said reservoir, lubricant displacing means in said reservoir

- actuated by said rod, a handle formed on the outer end of said rod, means for clamping said rod against movement, fixed supports for said reservoir, and wheel supports 5 positioned to carry the reservoir and fixed supports when the reservoir is tipped laterally by a force applied to said handle.
2. A lubricant compressor comprising a reservoir, an axially slideable rod extending 10 out through the top of said reservoir, lubricant displacing means in said reservoir actuated by said rod, a handle formed on the outer end of said rod, means for clamping said rod against movement, fixed supports 15 for said reservoir, wheel supports positioned to carry the reservoir and fixed supports when the reservoir is tipped laterally, and compressing mechanism housed under said reservoir between said fixed supports.
- 20 3. A lubricant compressor comprising a reservoir, a follower piston in said reservoir, an axial guide rod for said follower piston, said guide rod being axially slideable and extending out through the top of said reservoir, a detachable connection between said follower piston and said guide rod comprising a bayonet slot in one and a co-operating 25 projection in the other, said connection being capable of assembly by manipulation of the outer end of said rod, a handle formed on the outer end of said rod, means for clamping said rod against movement, fixed supports for said reservoir, wheel supports positioned to carry the reservoir and fixed supports 30 when the reservoir is tipped laterally, and compressing mechanism housed under said reservoir between said fixed supports.
- 35 4. A lubricant compressor comprising a reservoir, fixed tripod supports for said reservoir, wheel support positioned to carry the reservoir and fixed supports when the

reservoir is tipped laterally, and compressing mechanism housed under said reservoir between said fixed supports.

5. A lubricant compressor comprising a 45 reservoir, fixed supports for said reservoir, wheel supports positioned to carry the reservoir and fixed supports when the reservoir is tipped laterally, and compressing mechanism housed under said reservoir between 50 said fixed supports.

6. A lubricant compressor comprising a compression cylinder, a piston therein, a piston rod rigid with said piston and projecting beyond said cylinder, means for actuating the rod, and an annular check valve 55 encircling the rod and positioned to be unseated by the piston at the end of its stroke.

7. A lubricant compressor comprising low pressure compressing means, high pressure 60 compressing means fed by said low pressure compressing means, and an air vent plug for venting said low pressure means near its connection with said high pressure compressing means. 65

8. A lubricant compressor comprising a reservoir, high pressure compressing means supplied from said reservoir, a piston in said reservoir, an axially slideable rod extending 70 out through an end of said reservoir, a quick detachable connection between said piston and said rod, said piston normally detached from said rod, and an air vent plug for placing that part of the reservoir on the discharge side of said piston in communication 75 with the atmosphere, said rod and detachable connection constituting means for operating said piston to expel air from said reservoir through said vent plug.

In witness whereof, I hereunto subscribe 80 my name this 23rd day of March, 1925.

EMILE PIQUEREZ.
